UNITED STATES PATENT OFFICE.

JOHN S. FAYERWEATHER, OF RIDGEFIELD, CONNECTICUT.

DESIGN FOR HATS.

Specification forming part of Design No. 6,952, dated October 7, 1873; application filed September 12, 1873.
[Term of Patent 3½ years.]

To all whom it may concern:

Be it known that I, JOHN S. FAYERWEATHER, of Ridgefield, in the county of Fairfield and State of Connecticut, have invented a Design for a Hat, of which the following is a specification:

The nature of the design is fully illustrated in the accompanying drawing, in which—

Figure 1 is a perspective view of the hat; and Fig. 2, a profile of one side of the same, and which is referred to in the description.

It consists in a contraction in the side crown of the hat at some distance above the band, and in a cord arranged within a recess or hollow formed by this contraction.

A indicates the side crown of the hat; C, the band, and B the brim. The contraction in the side crown is designated by the letter *a*. It occurs a short distance above the band, and the cord D fits in it.

What I claim as my invention is—

The design for the hat having a contraction, *a*, in the side crown A thereof, as shown, and the cord D in said contraction, substantially as described.

J. S. FAYERWEATHER.
